UNITED STATES PATENT OFFICE.

FREDERICK JOHN LAUTERBACH, OF BROOKLYN, NEW YORK, ASSIGNOR TO WESTING-
HOUSE LAMP COMPANY, A CORPORATION OF PENNSYLVANIA.

INCANDESCENT LAMP.

Application filed April 21, 1919. Serial No. 291,738.

To all whom it may concern:

Be it known that I, FREDERICK JOHN LAUTERBACH, a citizen of the United States, and a resident of Brooklyn, in the county of Kings and State of New York, have invented a new and useful Improvement in Incandescent Lamps, of which the following is a specification.

This invention relates to the construction of a rugged type incandescent lamp and particularly to an improved means for resiliently supporting the filament.

There are many uses to which the present tungsten lamp is applied, which subject the lamp to excessive vibration, such as when used on street cars and battleships, in factory buildings, etc. This vibration produces strains in the mount carrying the filament which strains quite frequently cause an entanglement of adjacent strands of the filament, thereby changing the efficiency of the lamp or effecting its failure, and in the case of severe shocks the glass arbor, supporting the filament, is fractured. It is obvious that these strains are in every direction and, unless some shock absorbing means is provided, an early failure of the lamp may be predicted from the above and other reasons.

It is an object of the invention to provide a mounting for the filament capable of withstanding the stresses produced in any direction. In carrying this object into effect I resiliently support the usual glass arbor, said support being designed to absorb the shock of a blow given in any plane. Conjunctionively with this resilient support I use a special form of winding which has a tendency to positively maintain the adjacent strands of filament separate from each other.

In some types of rugged lamps, it is desirable to limit the vibration of the filament mount in the direction of the leading-in wires for the reason that the leading-in wires, being comparatively more rigid than the filament mount, do not vibrate with equal freedom, and this very often results in the breaking off of the leading-in wires from the filament at the point of their union, or a break in the filament strands connected thereto.

The special object of the invention is to provide a shock absorbing means which will retard the vibration of the filament mount

in a plane parallel to the plane drawn through the longitudinal axis of the leading- 55 wires.

Other objects of the invention will manifest themselves upon a reading of the following description.

Throughout the several views of the accompanying drawings similar reference characters refer to like parts.

In the drawings, Fig. 1 illustrates an elevation of a lamp mount embodying one form of my invention; Fig. 2 is an elevation 65 taken at 90° to that of Fig. 1; Figs. 3, 4, 5 and 6 illustrate modifications, considerably enlarged, of the connecting member between the lamp stem and its arbor; and Fig. 7 is a development of the manner in which the 70 filament is wound upon its supporting hooks.

Referring to the drawings, the lamp parts shown comprise a press or stem 1 into which the leading-in wires 2 are sealed, the inner ends thereof being connected with terminal strands of the filament 3. The filament 3 is supported upon a mount 4 comprised of a glass arbor 5, having a series of radially disposed hooks inserted into an enlargement 70 or button formed near each end of the arbor. The arbor 5 is joined to the press 1 by means of a connecting member or link 6, having its ends imbedded into the stem 1 and arbor 5. The link 6 may be of any formation, which will be more shock absorbing than a straight member of like material and not provided with weakened portions designed to have unequal shock resisting properties either axially or radially. I have illustrated several forms which the link 6 may be given, the preferred one being shown in Figs. 1 and 2. This style of link may consist of one or more closed loops formed intermediate the ends of a length of resilient material such as piano wire. The ends of the link 6 extend in opposite directions and are inserted into the adjacent glass elements so as to be in the axial line of both the bulb and the filament mount.

From an inspection of the drawings, it will be apparent that when the link 6 is provided with one or more closed loops, the greatest lateral resiliency will be in a direction perpendicular to the axial line of the loops and the arbor, thus a vibration of the arbor will

be retarded in all other directions. By the provision of this construction, any shock or jar will tend to vibrate the arbor in a pre-determined direction, namely, in the path of least resistance. The movement of the arbor will, therefore, be an oscillatory one about the axis of the loops.

Owing to the relatively large radius of the loops with respect to the diameter of the wire of which it is composed, the link may be constantly distorted without over-reaching the elastic limit of the metal, thus long service is possible since the metal is not fatigued and weakened to any appreciable degree. The leading-in wires as illustrated, are bent to angular form. One leg of each of the leading-in wires may be positioned in a common plane, substantially perpendicular to the axial line of the link. The other legs of the leading-in wires may be positioned in a plane substantially parallel to the axial line of the link. The free ends of the leading-in wires connect with the terminals of the filament 3 and the leading-in wires are caused to vibrate in unison with the arbor, thus avoiding to a considerable degree, the detrimental tension heretofore imposed upon the filament.

It will be appreciated that where the arbor and leading-in wires do not vibrate in harmony, the distance between the ends of the leading-in wires and the supports upon which the leading-in wires are disposed will vary and a stress will be imparted to the filament. The angular construction of the leading-in wire provides a compound pivot and it may move about the point adjacent the stem and about the apex of its angle.

The looped link in combination, therefore, with the angular leading-in wires, provides a construction which greatly relieves stresses on and reduces the possibility of rupture of the filament.

The form of link illustrated by Fig. 3 has a substantially closed loop intermediate its ends and may be flattened on opposite sides so as to be of less thickness in one direction than in another, as clearly illustrated by an enlarged end view. In this figure the loop is formed with the flattened surface on the inside, thus adding to the resiliency of the link when absorbing a shock received in a plane substantially parallel to that of the loop, and being more rigid when vibrated in a plane other than parallel to that of the said loop. Accordingly, when the form of link illustrated by Fig. 3 is employed, if mounted in such a manner that its loop is in a plane parallel to the planes in which each of the leading-in wires 2 are disposed, it has the same tendency to retard the vibration of the arbor in a direction perpendicular to the planes of said leading-in wires, as is characteristic of the link shown in Figs. 1 and 2.

The modification of the link shown in Fig. 4 contemplates the formation of three open loops positioned substantially 120° apart, and arranged one above another while Fig. 5 illustrates a somewhat similar formation consisting of two loops separated 180° .

If desired, the link 6 may comprise a straight piece of wire initially circular in cross-section and having had two of its opposite sides flattened, as illustrated in Fig. 6, so as to be more rigid in all directions except in the direction normal to its flattened surfaces. It is preferable to mount a link having this formation so that the flattened surfaces occupy planes at right-angles to that of the leading-in wires.

The material from which the connecting member or link 6 is made is an important item in that it must have special resiliency and strength to withstand the shocks absorbed by it for a period equal to the present life of a commercial lamp. If the wire from which the link is made is too springy or elastic, it will have a short life, whereas, on the other hand, if it is too rigid, it will fail to function properly. The cross-sectional area is another important factor to be taken into consideration in selecting a material or wire from which the link 6 is to be made, as the link must be inserted in the glass when in a plastic condition and the amount of heat absorbed by the metal comprising the link is liable to change the temper thereof and destroy its resilient property. I have found that piano wire of from 24 to 30 mils. in diameter is the most suitable for lamp of the smaller wattages, i. e., 25 to 50 watts. It is obvious that the general design of the link as to length, diameter, and number of loops will vary with the size of lamp in which the link is used.

In Fig. 7 I have illustrated a form of winding which has proved very effective for maintaining the adjacent strands of the filament separate, especially when used in combination with a shock absorbing link such as contemplated by my invention. In this form of winding, the filament is first attached to one of the leading-in wires, and it is then led to one of the upper hooks immediately thereabove, taken over to the adjacent hook of the same series, and brought downward to the hook of the lower series that is in alignment with the last mentioned upper hook. The filament is then wound over the adjacent hook of the lower series and brought back to a top hook, the method of winding being the same for the remaining hooks as just described. The filament after being strung upon the hooks has its free end secured to the other leading-in wire, which completes the winding operation.

While this invention has been set forth in certain preferred embodiments, it will be

understood that modifications may be made without departing from the spirit and scope thereof.

What is claimed is:

5. 1. In an incandescent lamp, a filament support including a stem, an arbor and a resilient support member joining said stem and arbor, said link being shaped to looped form between said stem and arbor, the loop 10 being positioned with its axial line substantially at right angles to the axis of the arbor.
  2. An incandescent lamp comprising an arbor having a filament supported thereon, a resilient supporting member connecting 15 said stem and said arbor, a loop intermediate the ends of said member, said ends being disposed upon the longitudinal axial line of said arbor and the axis of said helix being substantially at right angles to said axial 20 line.
  3. An incandescent lamp comprising a stem, an arbor, a resilient supporting member disposed substantially on the longitudinal axis of said lamp connecting said arbor 25 to said stem, a filament supported on said arbor, relatively-rigid leading-in wires embedded in said stem and having the ends thereof connected to the terminals of said filament and a helix in said resilient member 30 having the axis thereof substantially at right angles to the portions of said leading-in wires connected to said filament.
  4. An incandescent lamp comprising a stem, an arbor, a resilient member comprising
- ing a helix terminating in straight portions; 35 said portions being connected with said stem and arbor and positioned coincident with the longitudinal axis of the lamp, a filament supported on said arbor, leading-in wires embedded in said stem and having their free 40 ends secured to the terminals of said filament, said leading-in wires being bent to position a portion of their length adjacent to their exposed ends in parallel relation to the axial line of said arbor said loop in said resilient member having the axial line thereof substantially at right angles to the longitudinal axis of said portions of said leading-in wires. 45
5. An incandescent lamp comprising 50 a stem, an arbor, having a filament supported thereon, leading-in wires embedded in said stem and connected to the terminals of said filament, said leading-in wires having a portion of their length 55 parallel to and a portion of their length at right angles to the axial line of said arbor, a resilient supporting member having an end thereof embedded in said stem and an end embedded in said arbor, a 60 helix in said member disposed intermediate said ends and having the axis thereof substantially at right angles to the axial line of the arbor. 65

In testimony whereof, I have hereunto subscribed my name this 10th day of April, 1919.

FREDERICK JOHN LAUTERBACH.
